UNITED STATES PATENT OFFICE.

JONATHAN H. DUSTMAN, OF CLARKS, NEBRASKA.

CAR-COUPING.

SPECIFICATION forming part of Letters Patent No. 301,050, dated June 24, 1884.

Application filed December 15, 1883. (No model.)

To all whom it may concern:

Be it known that I, JONATHAN H. DUSTMAN, a citizen of the United States, residing at Clarks, in the county of Merrick and State of Nebraska, have invented certain new and useful Improvements in Car-Couplings, of which the following is a specification, reference being had therein to the accompanying drawing.

10 My invention relates to car-couplings; and it consists in the parts which will be herein-after described, and pointed out in the claims.

The figure in the accompanying drawing shows a perspective view of an end of a freight-car provided with my improvement.

15 A and B are two vertical rods. C is a hand-lever, to which the top of the rod A is secured. This hand-lever is pivoted at C to the top of the standard C².

20 D is a plate bolted to the roof of the car, to which the standard C² is fixed.

A' is a right-angled handle fixed to the rod A.

E is a crank-rod secured to the end of the car by hangers F F. Said rod is movably secured in the hangers—that is to say, it is adapted to turn therein.

E' is an arm projecting out from one side of the car and formed integral with the rod E.

25 E² is a crank projection of rod E. The lower end of the rod A is secured to the crank projection E².

30 E³ is a right-angled projection on the inner side of the rod E. The crank projection E² is inclined upward at about an angle of forty-five degrees from the plane of the arm E', as shown, so that when said arm gravitates after an operation the crank projection will not stop on the center—that is to say, when the arm E³ is down in a vertical line, the projection E² will extend slightly out from a vertical line, whereby the rod E may be turned and the arm E' and link-lifter E' may be raised by drawing up on the rod A. E, E', E², E³, and E' are formed integral of a single piece of metal.

35 G represents the draw-head, and H the link therein. I is the pin securing the link H in the jaws of the draw-head. I' is a short link pivotally fixed to the top of the pin I. J is a horizontal rod secured to the end of the car by straps J'. The rod J is adapted to turn in these straps at the convenience of the oper-

ator. J² is a crank projection on the rod J, to which the lower end of the rod B is secured. J³ is a crank-handle on the outer end of the rod J. B' is a handle on the rod B.

55 L is a foot-lever pivoted at L' to the roof of the car. The top of the rod B is secured to the outer end of said lever.

J⁴ is a right-angled projection on the inner end of the rod J. The outer end of this projection is jointed to the top of the short link I'.

60 The object of my invention is to facilitate and make safe the coupling of cars. To this end it consists in means whereby the link and pin may be controlled by the operator from 65 the side of the car, from the top, or from the platform of an approaching car.

The operation of my device is as follows: Assuming the car shown in the view standing still, and a car approaching, the operator may 70

guide the link into the approaching draw-head by means of the handle A' on the outer end of the rod A. By moving the handle in the position shown in the figure the link-guiding projection I' is raised up under the link, and 75 said link held in a position such that it will pass into the jaws of the engaging draw-head. When it is desired to effect the coupling from the top of the car, this can be done by raising up on the lever C. This action will produce 80 a result similar to that of moving I—that is to say, by raising up on the lever the link-guiding projection I' is brought under the link, and said link thereby guided into the jaws of the approaching draw-head.

When it is desired to uncouple the cars, this may be effected either from the top or the sides. By pressing down with the foot on end of the inner end of the foot-lever L the lower rod, J, is turned by 85 means of the rod B. This action forces up the arm J⁴, which is connected to the short link I', whereby the pin I is withdrawn from the draw-head and the cars uncoupled. By

40 turning the side handle, J³, the rod J is also turned and the rod J⁴ raised, and the pin 90 withdrawn from the draw-head. The handles A' and B' are intended, respectively, to guide the link or withdraw the pin at pleasure. These handles may be operated in coupling 95 the car to a flat car, a caboose, or other platform-car—that is to say, one can stand upon 100 a platform or the end of a flat car and control

the link and pin by means of the handles A' and B' and the intervening means. The mechanism herein shown is intended to be applied to each end of a car, so that a crank, I', will be relative on the right side of a car, and the crank J² and connective means on the left side, so that the car may be turned without affecting the relative position of the mechanism. The rods A and B are so placed on a car that 5 they do not interfere with the brakes. The link-guide mechanism is separate and independent from the pin-raising mechanism. The handle J³, when down, lies against the end of the car. In this position the pin is in 10 the draw-head. When the handle J³ is raised, said pin is not wholly withdrawn from the draw-head, but only sufficiently raised to permit the link to be withdrawn. The inner end of the foot-lever L on top of the car serves 15 as a stop to allow the upward movement of the pin—that is to say, by drawing in the handle J³, the arm J⁴ is raised and the pin I partly raised out of its seat. This action 20 forces up the rod B and raises up on the outer end of the foot-lever L. The inner end of said 25

lever is at the same time lowered and forced in contact with the roof of the car. This limits the upward movement of the pin.

Having thus described my invention, I claim as new and desire to secure by Letters Patent— 30

1. The hangers F, rod E, right-angled projection E', crank projection E², projection E³, and link-lifter E⁴, in combination with the rod A, provided with a handle, A', and the lever C, pivoted to the standard C², substantially as 35 described and set forth.

2. The rod J, secured to the end of the car by straps J', said rod being provided with handle J³, crank projection J², and arm J⁴, the link I', jointed to the top of the pin, and 40 the outer end of the arm J⁴, in combination with the rod B, having the handle B', and the foot-lever L, substantially as described, and for the purposes set forth.

In testimony whereof I affix my signature in 45 presence of two witnesses.

JONATHAN H. DUSTMAN.
